UNITED STATES PATENT OFFICE

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION

SELF-OPENING DIE HEAD

Substitute for abandoned application Serial No. 129,868, filed August 18, 1928. This application filed May 18, 1928. Serial No. 278,837.

This application is a substitute for application Serial No. 129,868 filed August 18, 1926.

My invention relates to an improvement in self-opening die-heads, the object being to produce a simple, compact, efficient and durable fixture constructed with particular reference to being tripped from the inside or the outside, according to the nature and 10 exigency of its use.

With these ends in view, my invention consists in a self-opening die-head characterized by having an axially-movable tripping-sleeve adapted to be tripped by an abutment 15 external to the fixture and also to be internally tripped through the agency of the work being threaded by the fixture.

My invention further consists in a die-head characterized as above and having certain 20 details of construction and combinations of parts as will be hereinafter described and pointed out in the claim.

In the accompanying drawings:

Fig. 1 is a view in side elevation of a self- 25 opening die-head embodying my invention;

Fig. 2 is a view thereof in front end elevation;

Fig. 3 is a view thereof in transverse section on the line 3—3 of Fig. 1;

Fig. 4 is a view of the die-head in central 30 longitudinal section, showing the fixture as closed, preparatory to a threading operation;

Fig. 5 is a corresponding view showing the 35 parts of the die-head in the positions due to them at the conclusion of a threading operation, and at the instant of the disengagement of the locking-plate from the adjusting-nut and before the operating-sleeve has been 40 moved rearward, which will instantly follow;

Fig. 6 is a corresponding view showing the parts of the die-head in the positions due 45 to them at the conclusion of the rearward movement of the operating-sleeve, which is accompanied by the retraction of the chasers;

Fig. 7 is a view of the die-head in transverse section on the line 7—7 of Fig. 1;

Fig. 8 is a broken detail sectional view on 50 the line 8—8 of Fig. 2;

Fig. 9 is a broken detail sectional view, showing a modified form of one feature of my improved fixture.

For the illustration of my invention I have shown it as applied to a self-opening die-head having a skeleton body 10 and an integral tubular shank 11, the said body being provided at its outer end with four equidistant radial grooves 12 for the reception of a corresponding number of chasers 13 having their inner ends threaded as at 14 and their outer ends beveled as at 15. The beveled outer end of each chaser co-acts with a bevel 16 in the inner corner of the outer end of an operating-sleeve 17 having rectilinear movement upon the skeleton die-body 10 aforesaid. Each of the chasers 13 is also furnished near its outer end with an inwardly-projecting operating-pin 18 engaged by a spring-actuated plunger 19 in a radial bore 20 in the said body 10, whereby the respective chasers are constantly urged to move into their expanded or retracted positions.

This said outward movement of the chasers takes place when the operating-sleeve 17 is moved rearwardly upon the body 10 by means of two oppositely-located operating-springs 21 located in bores 22 in the body 10 and at their projecting rear ends engaging the forwardly-facing shoulder 23 of the operating-sleeve 17.

For locking the operating-sleeve 17 in its forward or chaser-closing position against the tension of the said springs 21, in which position it holds the chasers 13 in their cutting positions, I employ a loosely-positioned ring-like locking-plate 24 having limited diametric movement in a groove 25 formed in the inner face of the reduced rear end of 90 the operating-sleeve 17.

For the initial entrance of said plate into the said groove, and also for the outward projection of the end of the operating-tongue 26 of the plate beyond the periphery of the reduced end of the said sleeve, the groove 25 is intersected by a radial cut 27 in one side of the rear end of the said sleeve, this cut being located in the plane of the groove 25 aforesaid, so as to virtually form a pas-

sage leading from the said groove to the periphery of the rear end of the sleeve.

The said plate 24 is formed with a large central opening 28, whereby it is adapted to 5 loosely embrace, as it were, an adjusting-nut 29 threaded upon the shank 11 for the adjustment of the cutting diameter of the chasers 13. At its forward end the nut 29 is reduced in diameter to form a forwardly-facing locking-shoulder 30 which is engaged by the rear face of that portion of the locking-plate 24 lying adjacent to the opening 28 therein and opposite to the operating-tongue 26 thereof, as shown particularly in 15 Fig. 4. A flat sheet-metal spring 31, lying in the bottom of the groove 25, provides for constantly urging the movement of the plate 24 into position for such locking engagement.

For guiding the plate 24 in its limited 20 diametric movements, I employ a pair of guide-pins 32 mounted in the operating-sleeve 17 and extending through its groove 25 at opposite points therein, in position to engage with flattened guide-surfaces 33 formed 25 upon the opposite side of the plate. A pair of similar pins 34 are also mounted in the sleeve 17 in position to engage with the opposite edges of the operating-tongue 26 of the plate, whereby the plate, although free for 30 limited diametric movement, is restrained from lateral displacement.

For disengaging the locking-plate 24 from the locking-shoulder 30 of the nut 29 to permit the operating-sleeve 17 to move into its 35 rearward or chaser-retracted position, the outer end of the tongue 26 is formed with a bevel 35 co-acting with the beveled forward wall 36 of a segmental notch 37 in the inner periphery of the rear end of a tripping-sleeve 38 which has rectilinear movement 40 upon the operating-sleeve 17.

The rear end of the said tripping-sleeve 38 is formed with an annular groove 39 designed to receive a yoke, or other suitable abutment, 45 properly located in the machine in which the die-head is used in the ordinary manner, and not shown herein. This groove 39 thus provides for the external tripping of the die-head by an abutment external to it and 50 mounted independently of it.

For the internal tripping of the die-head through the agency of the work itself, rather than through the agency of an external abutment, I provide a tripping-rod 40, centrally 55 located within the die-body 10 and mounted in a bushing 41 fitting into and having limited reciprocating movement in the bore 42 thereof. The said tripping-rod 40 is held in any desired position with respect to the said 60 bushing by means of a coupling-screw 43 extending radially between the bushing 41 and the tripping-sleeve 38, as shown in Fig. 4. To provide for the clearance of the screw 43 and for its radial reciprocation, the body 10 65 is formed with a radial slot 44, and the oper-

ating-sleeve with a corresponding slot 45. At its forward end, the rod 40 is provided with a T-head 46 secured in place by a pin 47 for insuring the actuation of the rod 40 by articles having a bore of larger diameter than the diameter of the rod, such as some 70 gauges of pipe.

As shown in Figs. 1 to 4 inclusive, my improved die-head is, in its closed position, ready for a threading operation, at which 75 time the locking-plate 24 is engaged with the shoulder 30 of the adjusting-nut 29 by the spring 31, whereby the operating-sleeve 17 is locked in its forward or chaser-closing position against the counter-urge of the springs 21. In this position of the plate 24 it holds the chasers 13 in their cutting positions 80 against the tension of their spring-actuated plungers 19 and the operating-sleeve 17 against the counter-urge of the springs 21, 85 the said plungers tending to move the chasers outward and the said springs tending to move the said sleeve rearward. At this time, also, the tripping-sleeve 38 is at the limit of its forward movement, as shown in Fig. 4.

At a predetermined point in the threading operation, during which the die-head is usually moved toward the work, though the work may be moved into the die-head, the tripping-sleeve 38 is arrested by the yoke, or other suitable abutment, set in the usual and well-known manner, according to the character of the work to be done, in the machine in which the die-head is being used. When the tripping-sleeve is thus arrested, its bevel 36 operates upon the bevel 35 of the operating-tongue 26 of the locking-plate 24 to diametrically move the same against the tension of the spring 31, so as to disengage the plate from the locking-shoulder 30 of the adjusting-nut 29, as shown in Fig. 5. The springs 21 now assert themselves to move the operating-sleeve 17 rearward with respect to the die-body 10, so as to permit the several chasers 13 to be moved radially outward away 100 from the work by their spring-actuated plungers 19. At the conclusion of the action 105 last described, the parts assume the positions in which they are shown in Fig. 6.

In case it is desired to have the die-head 110 automatically tripped through the agency of the work itself, instead of through the agency of an external abutment, as above described, the coupling-screw 43 is loosened and the tripping-rod 40 longitudinally moved in the bushing 41, as becomes necessary to trip the die-head at the predetermined point of its travel demanded by the given work to be done, after which the coupling-screw 43 is 115 tightened so as to form a rigid coupling between the tripping-sleeve 38 and the tripping-rod 40.

Now, in the use of the die-head the work, by impinging directly upon the forward end 120 of the rod 40, arrests the movement thereof 125

with the die-head, and hence the movement of the tripping-sleeve 38, whereby the locking-plate 24 is operated to trip the die-head in the manner already described.

5 It will thus be seen that my improved die-head may be tripped by an external abutment, or internally tripped through the agency of the work itself, as may be found most expedient, my die-head combining in 10 one unitary structure these two modes of tripping.

In Fig. 9 I have shown a modified form of locking-plate in which the tongue 26 of the plate 24, instead of having its outer end 15 beveled, is formed with a surface 48 lying at a right angle to its plane. Between this surface and the bevel 36 of the tripping-sleeve 38 I interpose a transmission member in the form of a ball 49. When now the tripping-sleeve is moved rearward in the manner described, its bevel 36 crowds the ball 49 radially inward, whereby the locking-plate is moved correspondingly for the release of 20 the locking-plate from the adjusting-nut, as 25 in the manner heretofore described.

I claim:

A self-opening die-head having a body formed with a central longitudinal bore and 30 with a radial clearance-passage intersecting the same, radially-movable chasers mounted in the forward end of the said body, a non-rotary chaser-operating sleeve axially-movable upon the said body and formed with a 35 radial clearance-passage registering with the said radial clearance-passage in the said body, a non-rotary tripping-sleeve axially-movable upon the said operating-sleeve and adapted to co-act with an abutment external 40 to the fixture, spring-means for normally urging the chaser-operating sleeve into its chaser-retracted position, a locking-member for holding the said chaser-operating sleeve in position for maintaining the chasers in 45 their cutting positions, a bushing having bearing in the bore of the said body and axially movable therein and itself having a central longitudinal passage intersected by a radial threaded bore, a tripping-rod located in the passage of the said bushing and 50 adjustably slidable therein, and a radially-arranged coupling-screw having its inner end threaded into the threaded bore of the bushing for engagement with the said tripping- 55 rod for clamping the same in position in the bushing and extending radially outwardly through the clearance-passages in the said body and operating-sleeve and into the tripping-sleeve through the periphery of which 60 it is available for being turned to clamp and release the said tripping-rod, whereby the tripping-sleeve and tripping-rod are connected together and the latter may be clamped and released for its adjustment from the out- 65 side of the tripping-sleeve, and whereby

chips and dirt are excluded from between the sleeves of the die-head.

In testimony whereof, I have signed this specification.

ALBERT F. BREITENSTEIN.
